United States Patent Office

Des. 211,610
Patented July 2, 1968

211,610

PROJECTION SCREEN CASE

Jasper S. Chandler, Rochester, N.Y., assignor to Eastman Kodak Company, Rochester, N.Y., a corporation of New Jersey

Filed Nov. 21, 1966, Ser. No. 4,747

Term of patent 14 years

(Cl. D61—1)

FIG. 2

FIG. 3

FIG. 1

FIG. 4

FIG. 5

FIG. 6

FIG. 7

FIG. 1 is a front elevational view of a projection screen case showing my new design in closed position;

FIG. 2 is a top plan view;

FIG. 3 is a left side elevational view;

FIG. 4 is a right side elevational view;

FIG. 5 is a bottom plan view;

FIG. 6 is a rear elevational view; and

FIG. 7 is a perspective view thereof in an open position.

I claim:

The ornamental design for a projection screen case, as shown.
